A diagram showing a central vertical line with horizontal bars extending from its top and bottom. This represents a 3D structure, likely a cylinder or a rectangular prism, viewed from an angle.

UNITED STATES PATENT OFFICE.

HARRY J. WERTHEIMER, OF CHICAGO, ILLINOIS.

POWER MOP.

Application filed January 16, 1926. Serial No. 81,727.

This invention relates to power mops and has for its object the provision of an efficient revolving mop which may be used for washing, dusting or polishing.

5 Another object is to provide means whereby a fluid may be continuously supplied to a mop or other polishing instrumentality during the operation thereof.

With the above and other objects in view, 10 as will be apparent, this invention consists in the construction, combination, and arrangement of parts all as hereinafter more fully described, claimed and illustrated in the accompanying drawings.

15 On the drawings:

Figure 1 represents a side elevational fragmentary view partly in section of a device embodying this invention.

Figure 2 is an enlarged fragmentary plan 20 view, partly in section and with the lower casing removed.

Figure 3 is an enlarged detail fragmentary view of the lower right hand portion of Figure 1.

25 As shown on the drawings:

The structure selected for illustration comprises a handle 1, which is integrally connected to the upper end of a tubular shaft 2. The shaft 2 has secured therein, an inner sleeve 3, which extends from the lower end of said shaft and is rigidly secured to the top of an inverted U shaped bracket 4. The lower ends of the arms of the bracket 4 are pivoted near the forward end of a pair of longitudinal brackets 5. The brackets 5 are rigidly connected through spaced brackets 6 to a vertical casing or housing 7. The housing 7 has a cylindrically shaped lower portion 8. A horizontal transverse bracket 9 extends between the brackets 5 and is rigidly connected thereto. A horizontal circular plate 10 is suspended from the bottom of each of the brackets 5. A bracket 11 is mounted on the plate 10 beneath the bracket 9 and has journalled therein a vertical shaft 12, the upper portion of which is journalled in said bracket 9. A pinion 13 is rigidly secured on the shaft 12 between the brackets 9 and 11. Four equally spaced vertical rollers 14 are mounted about the periphery of the plate 10 and are each provided with a peripheral groove 15. A rotatable ring or annular disc 16 is diametrically supported by the rollers 14, the inner periphery of said ring tracking 50 in the grooves 15 of said rollers. The ring 16

is rigidly connected through a plurality of peripherally spaced U shaped brackets 17, on the under side thereof, with a second ring 18, which supports a mop head which will be described hereinafter. The ring 16 has rigidly 60 secured thereon at its upper side, a plurality of peripherally spaced angle brackets 24, which support a horizontal annular gear 25 having its teeth on the inner periphery thereof in mesh with the pinion 13. 65

A circular plate 19 forming the mop head is supported by the ring 18. The plate 19 is of somewhat greater diameter than the portion 8 of the housing or casing which is concentric therewith. The periphery of the 70 plate 19 is secured in any suitable manner to a ring 20 for a purpose that will be apparent hereinafter. Polishing instrumentalities, in this instance, a mop fabric 21 of heavy woven material extends across the bottom of the plate 19 and is circular in shape. The periphery of the fabric 21 is provided with a hem 22 in which is positioned a tension spring 23, which is adapted to normally contract the hem 22 for stretching the fabric 21 over 75 the bottom of the plate 19. The spring 23 co-acts with the raised upper edge of the mop head caused by the ring 20, and thus prevents the mop fabric 21 from working off of said head. The gear 25, the rings 16 and 18, the plate 10, and the mop head 19 are substantially parallel and concentric with each other. 80

An electric motor 26 is suitably mounted within the appropriate casing 26' formed integral with shaft 2. The motor is operatively connected to an internal driving shaft 27, which extends through the upper end of the bracket 4 and is operatively connected to the shaft 12 through a universal connection 28. 90

The tubular shaft 2 has provided thereon a threaded hose connection 29 which communicates with the upper end of an internal tube 30, the latter extending downwardly through said shaft 2 into the housing 7 and communicating with a pliable hose connection 31. The hose connection 31 connects the lower end of the tube 30 with a nozzle 32 which extends centrally through the plate 10 and the mop head 19. A spring 33 surrounds the connection 31 so as to render the hose rigid. 100

The cover of the housing 7 is provided with a longitudinal slot 34 for permitting the shaft 2 to oscillate through the cover of the housing. A moveable tongue 35 of thin flexible 110

material (metal, leather or equivalent substance) surrounds the base of the shaft 2 beneath the inner edges of the slot 34 and slides between the upper side of the housing 5 and a pair of longitudinally extending transversely spaced guides 36, connected to the sides of said housing.

A switch 37 is conveniently mounted on the handle 1 and is electrically connected with 10 the motor 26 and the source of current therefor, for selectively controlling said motor.

It will be apparent that the foregoing device may be conveniently used for either washing, dusting or polishing and that the 15 same may be easily and economically manufactured.

Although the terms "mop" and "polishing means" are used herein and in the appended claims, these terms are not to be strictly limited 20 but are to be construed as including means for polishing, grinding, cleansing, washing and various operations.

I am aware that many changes may be made and numerous details of construction 25 may be varied through a wide range without departing from the principles of this invention and I therefore do not purpose limiting the claims otherwise than necessitated by the prior art.

30. I claim as my invention:

1. In a device of the class described, a stationary plate, a movable plate, an annular gear fixed to said movable plate, circumferentially spaced grooved rollers on said stationary plate, means engaging the grooves of 35 said rollers to support said movable plate, and driving means operatively associated with said gear.

2. The combination with a casing, of a 40 stationary plate mounted in the bottom of said casing, a rotatable plate below said stationary plate, polishing means detachably secured to said rotatable plate, driving means operatively connected to said rotatable plate, 45 and circumferentially spaced grooved rollers on said stationary plate, means rideable in the grooves of said rollers for supporting said rotatable plate.

3. The combination with a casing, of a 50 stationary plate, a rotary plate, polishing means detachably secured to said rotary

plate, an annular gear fixed to said rotary plate, a ring-like member positioned intermediate and secured to said gear and rotary plate, grooved rollers on said stationary plate, 55 means on said ring-like member rideable in the grooves of said rollers, and driving means operatively connected to said gear.

4. The combination with a casing, of a 60 stationary plate, a rotary plate, polishing means detachably secured to said rotary plate, an annular gear fixed to said rotary plate, a ring-like member positioned intermediate and secured to said gear and rotary plate, grooved rollers on said stationary plate, 65 means on said member rideable in the grooves of said rollers, driving means operatively connected to said gear, and fluid carrying means in communication with said mop.

5. In combination, a casing, an annular gear therein, a pinion in mesh with said gear, driving means pivotally connected to said pinion, a stationary plate in said casing, a rotatable plate without said casing normally carrying polishing means, rollers positioned 70 vertically on said stationary plate, means cooperating with said rollers operatively connecting said gear and rotatable plate for driving and supporting the latter, and fluid carrying means in communication with said polishing means.

6. In a device of the class described, driving means, a fixed member, grooved elements on said member, a movable member normally removably carrying polishing means, means 85 responsive to said driving means, and means rideable in the grooves of said elements for supporting said movable member and connecting the same to said responsive means.

7. In a device of the class described, a 90 fixed member, rollers mounted vertically on said member, a movable member normally carrying polishing means, means cooperating with said rollers connected to said movable member for supporting same, actuating means for said movable member, a handle for said device, and means carried by said handle for driving said actuating means.

In testimony whereof I have hereunto subscribed my name.

HARRY J. WERTHEIMER.
